FINGER COT

Gene B. Wong, Newcastle, Calif.

Application January 29, 1944, Serial No. 520,292

2 Claims.

(Cl. 294—25)

The present invention relates to personal accessories in the category of finger cots, finger stalls and the like and has reference to one which I have conveniently identified as a thumbner, the same being expressly, but not necessarily, adapted for picking up half-folded tissue wrappers from a box or container in a manner to facilitate the application to and wrapping around oranges and the like.

The surface finish of fruit wrappers is often glossy and when one called upon to pick up and utilize, let us say, some fifteen thousand wrappers per day, the use of bare fingers for such purposes is indeed a task beyond the comprehension of the average person. I am aware, of course, that different types of thimbles, finger cots and stalls are known and marketed and used in other lines of endeavor. Perhaps too, some of these devices could be satisfactorily employed in the line of endeavor with which we are here concerned. However, and notwithstanding this, I have evolved and produced a simple and expedient thumbner which, to my mind, aptly functions and fulfills the requirements of the trade.

More specifically, I have perfected a simple and expedient thumbner composed of two pieces of rubber, one rolled into sleeve form and the other applied as a patch thereto and overlapping the parallel edges of the first-named part to provide an open-ended stall which is generally used on the thumb but can be, if desired, applied to the second finger as is sometimes just as advantageous and useful in wrapping operations.

Other features and advantages will become more readily apparent from the following description and the accompanying illustrative drawing.

In the drawing, wherein like numerals are employed to designate like parts throughout the same:

Figure 1 is a perspective view showing a thumbner in use.

Figure 2 is an enlarged perspective view of the thumbner per se.

Figure 3 is a central cross-sectional view of the same.

The thumbner as a unit is denoted by the numeral 4. It is of tapered open-ended form to apply either to the thumb or the second finger of the right hand, as a general rule. It is made up of two pieces of rubber. The first piece, which is a rectangular blank 5 is rolled into substantially tubular form with its adjacent edges spaced apart. The working surface of this is slightly roughened to facilitate grasping the paper. The second piece is a patch 6 superimposed upon the first piece and glued or otherwise secured to the edge portions 7. With these edge portions spaced apart the patch overlaps said edge portions and

defines a channelway which is in effect a ventilating groove. This also allows for expansion and contraction, radially. The patch is of a length corresponding to the length of the main body portion 5. The latter can be a section from an old discarded inner tube with its surface roughened for purposeful use. The part 6 may be an ordinary tire patch. Hence, the elements are available for use at this time despite the restrictions on rubber and other difficulties attending manufacture and use thereof.

The degree of taper is generally such that the narrower or smaller end protrudes beyond the thumb nail, this to serve as a guard and to protect against tearing the wrapper.

The ordinary wrapper A as shown in Figure 1 is partly folded between its ends as at B into half-sections C. Applying the thumbner to the thumb it is picked up in folded form and then slipped down over the fruit, the fruit being held in the left hand and the wrapping task is completed.

The use of this simple and expedient thumbner has proved to be a boon to the user. It is of utmost simplicity and economical and constitutes an ideal time and labor saver.

It is thought that persons skilled in the art to which the invention relates will be able to obtain a clear understanding of the invention after considering the description in connection with the drawing. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. A thumbner comprising a tubular body formed from a sheet of rubber having its side edges spaced from each other to provide the body with a channel extending the full length of the body and open at both ends thereof, and a second sheet of rubber extending along the body the full length thereof in bridging relation to said channel and adhesively secured flat against the outer surface of first sheet at opposite sides of the channel.

2. A thumbner comprising a tubular body tapered towards its front end and formed with a channel extending longitudinally of the body and open at its ends, and a sheet of elastic material extending substantially the full length of said body in bridging relation to said channel and secured in face-to-face engagement with portions of the body at opposite sides of the channel.
